UNITED STATES PATENT OFFICE.

JOHN C. FIDDYMENT, OF BALTIMORE, MARYLAND.

PRESS.

1,219,279.

Specification of Letters Patent. Patented Mar. 13, 1917.

Application filed August 31, 1915, Serial No. 48,155. Renewed January 26, 1917. Serial No. 144,773.

To all whom it may concern:

Be it known that I, JOHN C. FIDDYMENT, a citizen of the United States, residing at Baltimore, in the State of Maryland, have 5 invented certain new and useful Improvements in Presses, of which the following is a specification.

This invention relates to improvements in presses and has particular reference to 10 a press for extracting fluids from matter by compressing such material during its travel through a chambered receptacle whose area preferably decreases toward the discharge end of the press.

15 The means employed to effect this decrease in the area of the chambered receptacle may vary it being common to sometimes produce the tapering chamber by tapering the body of the conveyer or by tapering the shell about the conveyer.

20 Heretofore it has been common in presses to employ conveyers having spiral threads either broken or continuous by means of which the material to be pressed is advanced 25 through a perforated, slatted or foraminous shell or casing. In presses of this character it is not infrequent that the material will so cling to the body of the screw that it will simply revolve therewith and not advance, 30 or in mushy or semi-solids will even sometimes flow backward toward the feed-in-end.

35 My invention has for its object to provide a press with an improved construction of conveying means whereby to either entirely avoid the use of an advancing screw or simply to employ such screw at or near the discharge end and to positively push and force the material forward during each 40 revolution of the machine.

Another object of the invention is to provide an improved conveying means having a revolving body with a plurality of annular channels which latter are blocked, and 45 provided with lateral escape passages to afford communication between one channel and another.

50 The invention therefore may be used in connection with inclosing shells or casings that vary widely in construction.

With these and other objects in view, the accompanying drawings illustrate embodiments of the inventive idea, it being understood however that the drawings do not 55 define the limits or scope of the invention.

In the drawings,—

Figure 1, shows a vertical longitudinal section through a machine embodying the invention.

Fig. 2, illustrates a cross-sectional detail 60 through the same,—the section being taken on the line 2—2 of Fig. 1.

Fig. 3, shows in perspective, one of the detached division plates.

Fig. 4, illustrates a longitudinal section 65 through a machine embodying the invention but of a slightly modified form, and

Fig. 5, shows a cross-sectional view through the latter,—the section being taken on the line 5—5 of Fig. 4.

In the present disclosure of the invention I make use of a casing or shell and some other details shown in my prior Patents 1,049,834 and 1,069,404 to which the usual feed-in-hopper is attached so as to effect 70 a continuous feeding of material to be pressed.

In carrying out my invention I employ a shell or casing 10, which may be formed of sections 11, so as to conveniently provide 80 a series of circumferential openings or escape passages 12, for the outlet of the expressed fluids.

In the present instance these shell or casing sections are shown secured together by 85 means of long bolts or bars 13, which latter pass through suitable eyes 14, that are cast on each section, as clearly shown in Fig. 2. By means of this sectional construction of shell and casing, liners 15, of suitable size 90 may readily be inserted between the sections to vary the area of the openings or escape passages to suit the character of the material that is being pressed.

On the interior of the casing or shell I 95 provide a body 16, which extends longitudinally of the shell and which is suitably mounted on a shaft 17, that is sustained in bearings 18 and 19, respectively. This shaft may be driven in any suitable manner to 100 effect a revolution of body 16 and also to revolve a gear 20, carried thereon for a purpose which will presently be described.

The body and the inner circumferential wall of the casing or shell sections are so 105 shaped as to provide a tapering chamber 21, through which the materials are conveyed so as to effect a compression thereof to express the fluids.

One of the objects of my present inven- 110

- tion is to provide improved means for advancing the material through the tapering channel from the feed or inlet end without depending upon a screw to effect such advance, and to do this I provide the body 16, at the feed-in-end with a plurality of spaced-apart circular partitions 22, preferably of uniform diameter, so as to produce a series of annular circumferential channels 23. Each annular channel is provided with one or more cross-wise baffle plates 24, and at each baffle each partition has a side opening 25, that forms a lateral outlet or communication from one channel to the next channel in advance of it, so that material in any given channel 23, must remain in that channel until it passes through one of the lateral openings or outlets 25, into the next channel. The number of these partitions and annular channels on the body 16, may be varied, but in the form of device shown in Fig. 1, they terminate somewhat near a point midway between the ends of the body 16, and said body is then provided with a tapering screw thread 26, that extends toward the discharge-end of the body, which threads will also convey the material through the tapering chamber 21, and continue its pressing. In order to compel the material to discharge from one annular channel into another through the lateral openings, I provide a lower shell or casing partition 27, at the feed-in-end and beneath said channels and partitions 22. A shaft 28, extends through the lower shell and carries a plurality of heads 29, each of which latter register with and project into an annular channel around the body 16. These heads 29, may also vary in shape but in the form shown in Fig. 1 they are circular so that their circumferences may travel in close proximity to the circumference of the body 16. A gear 30, is provided on shaft 28, which meshes with and is driven by the gear 20, so that when the body 16, revolves, the heads 29, will also revolve, but in a reverse direction,—each head turning in a vertical plane in registration with an annular channel on the body.

As each head 29, travels in a channel 23, around the body 16, and each channel has one or more cross-wise baffles 24, it is obvious that cross-wise notches 31, must be provided in the heads into which said baffles may project during each revolution. In the sectional view shown in Fig. 1, the notch 31, in the innermost head 29, and the baffle 24, in the innermost channel are illustrated as coming into registration, so that close contact between the heads and channels may be maintained.

It will be noted that the heads 29, are slightly spaced by means of washers 32, so

they will be held in alignment with the respective channels.

Inasmuch as the heads 29, are spaced to enable the edges of the partitions 22, to project between them, such spaces, unless closed, will permit material to pass therein and back up at the feed end. To overcome this I provide a plate 33, with a concave upper edge 34, which closely fits the spaces referred to and whose curved edge 34, engages the curved circumferential edge of the partition 22, so as to effectively close said spaces.

In the operation of the machine the material is continuously fed to the outermost annular channel 23, and during rotation of the body 16 and the heads 29, the latter, by entering and filling the channel, will prevent the material from traveling around with the body in one direction while the baffle 24, will prevent the material from flowing around the channel in the reverse direction. During rotation, however, the baffle gradually approaches the head consequently the material in the channel between the baffle and head will be subjected to compression and obviously will be forced laterally through the opening 24, into the next annular channel. When the baffle is in position to pass over the head beneath it, the latter will present its notched edge 31, to receive the baffle 24, and allow the latter to pass. Immediately upon passing the baffle the head again compresses the material in the annular channel and causes it to seek outlet through the lateral opening into the next channel. This operation is repeated so that the material will be held against movement in a circular direction about the body and only shift laterally through the side openings 25, as the baffles and the circular heads are brought toward each other in each revolution. By this means the material is positively forced from one annular channel to another and thereby advanced toward the discharge end of the machine, where the screw threads 26, if present will take up the material and continue its advancement and compression because of the continued reduction in the size of the tapering chamber 21.

A cone-shaped head 35, is provided at the discharge end of the shell and is adjustable on the body to enable the outlet 36, to be increased or decreased as desired.

In the form of device illustrated in Fig. 4, the body is formed of sections 38, and the partitions 39, are so spaced as to produce annular channels 40, of gradually reduced areas as they recede from the inlet or feed-in-end. Also in this form the continuously rotating heads are omitted and intermittently movable heads 41, are substituted which heads form stationary abutments in the channels 40, against which the materials are compressed during the revolution of the body. The movable baffles 42, substantially

like those designated 24, in Fig. 1, are employed and the lateral openings 43, like those designated 25, in Fig. 1, are also provided in this modified form.

- 5 The heads 41, in the modified form are provided with a series of circumferential recesses 44,—the curved walls of which recesses serve as stationary abutments to prevent rotation of the material with the body 10 and the partitions. The circumference of each head 41, between two recesses is concave as at 46, so as to seat against the curved body and be held against rotation during each revolution of the body. When, however, a baffle engages the curved wall of a 15 recess, the head will be given a partial rotation until said baffle has passed whereupon said head will again be held against movement.
- 20 By referring to Fig. 5, it will be understood that the body 38, partition 39 and baffle 42, all turn together; that partition 39, has a lateral opening 43, in front and to one side of the baffle and that the material 25 to be advanced will fill the annular channel 40, all the way around from the baffle to the intermittently-movable abutment. Therefore, as the baffle, body and partition 30 turn, the material will collect in front of the baffle and move laterally through the opening 43, into the next channel.

In this modified form of device the intermittently-movable heads 41, are all idle on a shaft 47, and turn independently when 35 either of them is engaged by a baffle, which obviously is once during each revolution of the body.

It will be noted that as the capacity of the first annular channel is greater than the 40 area of the next channel, the material must be compressed to force it into the second channel and still further compressed to force it into the third channel. In this way the fluids are expressed from the materials and the transfer of the material from 45 one channel to the other is positive during each revolution.

Beyond the series of annular channels the body is hollow and the fluids may thus find 50 an escape through the annular spaces 48, formed between the sections.

An adjustable cone-head 49, at the discharge-end will choke the outlet 50, so as to maintain the compression of the material 55 after it leaves the annular channels.

The body 38, in the modified form is carried on a shaft 51, that is driven by a gear 52.

The plates 33, with concave upper edge 34, are also employed in the modified device 60 to engage the partitions 39, and prevent escape of material between the heads 41.

Having described my invention what I claim is,—

1. In a press the combination with an 65 outer shell to receive materials to be pressed,

of a rotating body extending longitudinally in the shell and provided with a plurality of circumferential channels which decrease in area as they recede from the feed end and each channel having an opening leading 70 to another and smaller of said channels, and means continuously projected in each of said channels to force the material from one channel to another.

2. In a press the combination with an 75 outer shell to receive the material to be pressed and provided with fluid escape openings, of a body mounted in the shell so as to revolve therein said body having a plurality of annular circumferential channels with means in each channel to block the same,—said channels being provided with lateral passages which provide communication with another of said channels, and means continuously projected in and 80 coacting with each channel to force the material from one channel through the lateral passages to another channel.

3. In a press the combination with an 85 outer shell, of a body extending longitudinally of and mounted to revolve in the shell said body having a plurality of circumferential channels with means to block each channel and with lateral escape passages in the channels, and means projecting in each 90 channel and mounted to be rotated whereby to force the material through the lateral escape passages from one channel to another.

4. In a press the combination with an 95 outer shell, of a body extending longitudinally of and mounted to revolve in the shell said body having a plurality of circumferential channels which decrease in area as they recede from the feed end,—each channel being blocked circumferentially to interrupt its continuity and having a lateral passage that forms a communication between a channel of greater area with another channel of lesser area, and means always projecting into each channel to prevent rotation and back-flow of the material with 100 respect to the body.

5. In a press the combination with an 105 outer shell, of a body extending longitudinally of and mounted to revolve in the shell 115 said body having a plurality of spaced circumferential partitions to form annular channels and having lateral passages to provide communication between one channel and another and rotatable heads projecting 120 between the partitions and into said channels whereby to prevent rotation and back-flow of material with respect to the body and to force the material from one channel through the lateral passage to another channel. 125

6. In a press the combination with an outer shell to receive the material to be pressed and provided with fluid escape openings, of a body mounted in the shell 130

so as to revolve therein said body having a plurality of spaced circumferential partitions to form annular channels that extend part of the way only about the body said channels having lateral passages to provide communication with other of said channels; rotatable heads projecting into the channels and plates projecting between adjacent heads and engaging the circumferential partitions.

7. In a press the combination with an outer shell, of a rotatable body in the shell; a plurality of spaced partitions extending about the body and each partition having a lateral bend and rotatable means projecting into the spaces between the partitions and provided with means to receive the lateral bends in the partitions.

8. In a press the combination with an outer shell, of a rotatable body in the shell; 20 a plurality of spaced partitions extending about the body and each partition having a lateral bend,—the spaces between the partitions decreasing in area as they progress from the feed-in-end, and rotatable means 25 projecting into the spaces between the partitions said rotatable means having recesses to receive the lateral bends in the partitions.

In testimony whereof I affix my signature in presence of two witnesses.

JOHN C. FIDDYMENT.
